UNITED STATES PATENT OFFICE.

PETER BLATT, OF ALLEGHENY, PENNSYLVANIA.

DUMPING-WAGON.

No. 823,253.

Specification of Letters Patent.

Patented June 12, 1906.

Application filed December 12, 1905. Serial No. 291,422.

To all whom it may concern:

Be it known that I, PETER BLATT, a citizen of the United States of America, residing at No. 504 Allegheny avenue, Allegheny, in the county of Allegheny and State of Pennsylvania, have invented certain new and useful Improvements in Dumping-Wagons, of which the following is a specification, reference being had therein to the accompanying drawings.

This invention has relation to dumping-wagons, and relates in particular to that class of dumping-wagons wherein the bottom of the wagon is composed of two hinged sections, the sections being hinged to the sides of the body or frame of the wagon and with their free edges meeting on a line running longitudinally of the wagon at the center thereof.

In a wagon constructed according to my invention I propose to provide one of the hinged sections of the bottom with a metal plate, which when the sections are in closed position will overlap the meeting edges of the two sections upon the upper side, so as to prevent the contents of the wagon from falling or sifting through the space between the meeting of the adjacent edges of the two sections, and as this plate is carried by one of the movable sections of the bottom it is necessary that the section carrying the plate should close before the other section; otherwise the required closure of the two sections in the proper position could not be secured, and I have therefore provided novel means for closing the two sections of the bottom, whereby that section which carries the plate will always be closed first.

The novel means which I have provided whereby one section of the bottom will always be closed prior to the closing of the other section is also applicable to hinged bottom sections wherein the plate above referred to is dispensed with, and in this connection the said novel means for closing the bottom sections prevents the free edges of the same coming together and locking in an angular position before they have reached their proper horizontal position against the body or frame of the wagon.

Another object of my invention is to provide, in connection with the above-mentioned means for closing the hinged bottom sections, novel means for locking and releasing the closing means. Other objects and the means whereby they are accomplished will be developed in the following specification.

tion; and my invention consists in the novel construction, combination, and arrangement of parts hereinafter described and claimed.

Referring to the accompanying drawings, illustrating my improvements, in the several figures of which like reference-numerals designate corresponding parts, Figure 1 is a side elevation of a dumping-wagon constructed according to my invention. Fig. 2 is a vertical longitudinal sectional view of the same. Fig. 3 is a vertical transverse sectional view on the line $x-x$ of Fig. 1. Fig. 4 is a rear elevation of the same. Fig. 5 is a fragmentary detail sectional view of the winding and releasing mechanism for the bottom-closing means on an enlarged scale. Fig. 6 is a fragmentary view showing in elevation the mechanism shown in Fig. 5. Fig. 7 is a fragmentary side elevation of the brake mechanism of the wagon. Fig. 8 is a top plan view of the brake mechanism shown in Fig. 7. Fig. 9 is a detail perspective view of the brake-lever. Fig. 10 is a fragmentary detail view, on an enlarged scale, of a portion of the front end of the wagon and of the movable bottom sections, and Fig. 11 is a similar view of a portion of the rear end of the wagon and of the movable bottom sections.

The side boards or frames of the wagon (designated 1 in the drawings) are mounted on a front axle 2 and a rear axle 3, and these axles carry, respectively, front wheels 4 and rear wheels 5. The side frames or boards 1 of the wagon are provided with a front board 6 and a rear or tail board 7, these parts being angularly disposed and permanently secured to the side boards or frames 1 by metal angle-strips 8, 9, respectively.

Above the side boards or frames 1 and the front board and rear board 6, 7 are mounted side boards 10, 11 and front and rear boards 12, 13, the side boards 10, 11 and front boards 12, 13 being an upward extension of the wagon-body and being united thereto by bent bars 14, which latter also constitute members of the hinges by which the movable bottom sections are united to the frame or body of the wagon.

The movable bottom of the wagon is composed of two hinged sections, (designated, respectively, 15 and 16, the section 15 being hinged to the straps 14 on one side of the body by means of hinged members 15', while the section 16 is hinged to the straps 14 on the other side of the body by hinged members 16'.) The bottom section 15 carries a

metal plate 17, that is rigidly secured upon the upper surface of said section 15 and extends from end to end thereof, and also extends somewhat out beyond the edge of said section 15, so as to overlap the adjacent edge of the section 16. Along the under side of the section 15 and adjacent the inner edge thereof is fixed a beam or brace 18, and along the edge of the section 16 a similar beam or brace 19 is fixed, these beams or braces projecting at both ends slightly beyond the ends of the sections 15 and 16 and the beams or braces being thicker at their middle than at their ends, as clearly shown in Fig. 2 of the drawings. The beam 18 carries on its forward end a sheave 20, which is rotatably mounted in a bracket 21, and on its rear end an eyebolt 23, these parts being employed for the reception and guidance of a chain 24, which serves, in connection with mechanism hereinafter described, as the means whereby the movable sections of the bottom are closed. The beam 19 is formed with a vertical groove 25 at its front end, a staple 25' spanning this groove, and with a similar vertical groove 26 at its rear end and a staple 26' spanning the groove 26, and with a staple 22 at its center, said grooves and staples serving to receive and sustain in proper position the chain 24, above referred to.

Upon the outer surface of the front board 6 a bracket 27 is arranged, and in this bracket is journaled a sheave 28, over which the chain 24 passes, and a bracket 29 is carried by the rear board or tail-board 7, and in the bracket 29 is journaled a sheave 30, the chain 24 also passing over the sheave 30. The course of the chain 24 is as follows: Beginning with the eyebolt 23, to which the chain is attached, the chain passes over the sheave 30 and then down over the rear end of the beam 19 through the staple 26', thence along the lower surface of said beam 19 and in contact with the said surface through the staple 22, upwardly through the groove 25 and staple 25' on the front end of the beam, thence over the sheave 28 and around the sheave 20 on the end of the beam 18, and thence up and around a roller 31, which is journaled in the side boards or frames 1 1. The chain, it will be observed, passes over but one sheave on the hinged bottom sections, this sheave being carried by the beam 18, and it will also be observed that the chain is in frictional contact with the lower surface of the beam 19 through the length of that beam, and this arrangement is of particular importance, for the reason, as will be hereinafter shown, that this frictional contact of the chain with the surface of the beam 19 has a controlling effect upon the successive closing of the bottom sections.

The roller 31 carries a ratchet-wheel 32 at one end, the ratchet-wheel being fast on the roller, and a lever 33, having a suitable han-

dle 34, which is mounted on the roller between the ratchet-wheel 32 and the adjacent side board or frame 1. The lever 33 carries a pivotally-mounted swinging pawl 35, that is adapted to engage the teeth of the ratchet-wheel 32, and a pivoted dog 36 is mounted in a bracket 37, that is attached to the end-board 6. The dog is formed with a shoulder 37' at its free end that engages the teeth of the ratchet-wheel and is also formed with a forwardly-projecting nose 38, which is slightly turned up on its outer end, as at 39, and the lever 33 carries a laterally-projecting pin 40, which is located near one edge of the lever and is adapted at a certain position of the lever 33 to pass over the nose 38 of the dog 36 and rest just above the upper surface of the same. The lower end of the lever 33 is extended laterally of the lever, as at 41, and this laterally-extending end of the lever is formed with a lug or projection 42 at its extremity, which lug is adapted at a certain position of the lever 33 to strike the lower edge of the dog 36 and raise this dog out of engagement with the ratchet-wheel 32.

A suitable brake is provided, this brake comprising a rock-shaft 43, having forwardly-extending arms 44 44, that carry brake-shoes 45, engaging the rear wheels 5. The rock-shaft 43 carries a lever 46, to which is attached a rod 47, extending to the front of the wagon and there attached to a pivoted lever 48, which is arranged so as to move in a slot 49 in a bracket 50, said slot being provided with teeth 51 on one edge that are engaged by a tooth 52 on the lever 48.

The parts constructed and arranged as above described are operated in the following manner: When the wagon is loaded and the bottom sections closed, the latter are maintained in their closed position through the medium of the chain 24, the roller 31, and the parts appurtenant to the roller. These appurtenant parts are best shown in Figs. 5 and 6, and, referring now to these figures, it will be observed that the dog 36 is in engagement with the ratchet-wheel 32 and is held in locked position by the pin 40 on the lever 33, which in the position of the lever shown in full lines is one at a slight angle to the perpendicular. In this position of parts the pawl 35 is inactive and rests upon one of the teeth of the ratchet-wheel 32. Now if it be desired to dump the load from the wagon the pawl 35 is lifted by the hand and the lever 33 is moved around in the direction of the long arrow X to a horizontal position, and, as shown by the short dotted lines in Fig. 5, the lug or projection 42 toward the ends of the movement of the lever to this position engages the lower surface of the dog 36 and lifts the same, so as to entirely disengage it from the ratchet-wheel 32, and thus allow the ratchet-wheel and the roller to turn under the traction of the chain and allow the chain to

unwind and the movable sections of the bottom to drop down and discharge the load.

When it is desired to close the movable sections of the bottom, the lever 33 is raised to a position above the horizontal position, preferably to the position shown by the long dotted lines in Fig. 5, this movement of the lever permitting the dog 36 to drop down into engagement with the ratchet-wheel. The pawl 35 is also allowed to drop into engagement with the ratchet-wheel, and upon moving the lever 33 alternately in opposite directions the ratchet-wheel will be rotated through the medium of pawl 35 and dog 36 and the chain 24 will be wound up on the roller. The first few movements of the lever 33 will take up the slack of the chain between the sheave 28 and the roller and will raise the bottom section 15 to a horizontal position previous to any movement of the bottom section 16, the reason for this peculiar and novel action being that the portion of the chain 24 passing under the bottom of the beam 19 in frictional engagement therewith is less readily movable than the portion that extends between the sheave 28 and the roller, and consequently the last-named portion of the chain will first be wound upon the roller and will elevate the section 15 before any movement is imparted to the section 16. After the bottom section 15 has been raised to the horizontal position shown in full lines in Fig. 3 the continued movement of the lever 33 will result in further winding of the chain upon the roller 31, and eventually when all the slack of the chain has been taken up the section 16 will be brought up to a horizontal position and into contact with the lower surface of the plate 17, carried by the section 15. After the bottom sections have been closed by the operation of the lever 33 in the manner above described the lever is thrown over into the position shown in full lines in Fig. 5, thereby locking the dog 36 in engagement with the ratchet-wheel 32 and preventing accidental disengagement of the dog by the jolting of the wagon or by any other means than the movement of the lever 33 to a position where the pin 40 is removed from above the nose 38 of the dog 36. Accidental movement of the lever is somewhat guarded against by the upturned outer end 39 of the nose 38, which during any jolting movement of the wagon would be thrown upwardly by the upward movement of the dog produced by such jolting and would be thereby thrown in front of the pin 40 and tend to prevent the lever 33 from assuming a vertical position.

From the foregoing description it will be observed that it is impossible in closing the bottom sections to close the section 16 until after the section 15 has been closed, and this feature is of particular importance whether or not the section 15 is provided with thelapping plate 17, as otherwise if the two movable sections 15 and 16 were moved simulta-

neously they would be liable to come into contact at their edges while in an angular position relatively to the bottom of the frame just before reaching their full closed horizontal position and to jam at this position, leaving a triangular opening at each end, which after the wagon is loaded would permit of the escape of its contents.

In Fig. 3 of the drawings I have shown the section 15 in dotted lines in one of the positions which it assumes while being closed, the direction in which it is closed being indicated by a dotted arrow, and in the same figure of the drawings I have shown the section 16 in dotted lines in the position which it retains 80 during the closing movement of the section 15, and the section 16, it is to be understood, will retain the position shown in dotted lines in Fig. 3 until the section 15 is drawn up to the fully-closed position shown in dotted lines 85 in this figure.

I am aware of the fact that a dumping-wagon has been constructed wherein movable bottom sections are operated by means of a chain arranged somewhat similarly to 90 the manner in which I arrange the chain; but in the dumping-wagon referred to one of the movable bottom sections is provided with a single sheave and the other with a sheave at each end, and under this arrangement it is 95 impossible to obtain the frictional engagement of the chain with one of the bottom sections, which, as above described, effects the successive closing of the bottom sections.

I claim—

1. In a dumping-wagon, the combination with a body portion, of two bottom sections, each hinged at one edge to the body, a beam carried by the free edge of each bottom section, a sheave carried on one end of one of said beams, a sheave mounted at each end of the body portion, a roller mounted on the body portion, means for rotating said roller, and a chain connected at one end to the end of the beam which is provided with a sheave 110 and passing over one of the sheaves on the body portion, thence down to the other of said beams, along the same in frictional contact with the lower surface thereof, thence upwardly around the other sheave on the 115 body portion, thence around the sheave on the first-named beam, and thence around said roller.

2. In a dumping-wagon, the combination with a body, movable bottom sections hinged to the body, and a chain connected to said bottom sections, of a roller to which said chain is connected, a ratchet-wheel carried by said roller, a dog pivotally attached to the body and engaging said ratchet-wheel, said 125 dog being provided with a forwardly-projecting nose, a pivoted lever, a pivoted pawl mounted on said lever, a pin carried by said lever and adapted at one position of the lever to extend over the nose of the dog, thereby 130

locking the dog in engagement with the ratchet-wheel.

3. In a dumping-wagon, the combination with a body and movable bottom sections, of 5 a chain connected to said bottom sections, a roller connected to said chain, a ratchet-wheel carried by said roller, a pivoted lever, a pivoted pawl carried by said lever and engaging said ratchet-wheel, a dog pivotally mounted on the wagon-body, engaging said ratchet-wheel, a pin carried by said lever and adapted at one position of the lever to extend
- over said dog, and a projection or lug carried by the lever and adapted at another position of the lever to strike the under side of said 15 dog and release it from engagement with the ratchet-wheel.

In testimony whereof I affix my signature in the presence of two witnesses,

PETER BLATT.
